(57) **CLAIM**

The ornamental design for a sanding block, as shown and described.

DESCRIPTION

FIG. 1 is a front-right perspective view of our sanding block according to our new design;

FIG. 2 is a front-left perspective view thereof;

FIG. 3 is a front-right bottom perspective thereof;

FIG. 4 is a front-left bottom perspective view thereof;

FIG. 5 is a front view thereof;

FIG. 6 is a rear view thereof;

FIG. 7 is right-side view thereof;

FIG. 8 is a left-side view thereof;

FIG. 9 is a top plan view of each element of our sanding block, shown side-by-side;

FIG. 10 is a bottom plan view of each element of the sanding block, shown side-by-side;

FIG. 11 is a front-right perspective view of our sanding block, shown as fully assembled;

FIG. 12 is a front-left perspective view of our sanding block, shown as fully assembled;

FIG. 13 is a front-right bottom perspective of our sanding block, shown as fully assembled;

FIG. 14 is a front-left bottom perspective view of our sanding block, shown as fully assembled;

FIG. 15 is a front view of our sanding block, shown as fully assembled;

FIG. 16 is a rear view of our sanding block, shown as fully assembled;

FIG. 17 is right-side view of our sanding block, shown as fully assembled;

FIG. 18 is a left-side view of our sanding block, shown as fully assembled;

FIG. 19 is a top plan view of our sanding block, shown as fully assembled; and,

FIG. 20 is a bottom plan view of our sanding block, shown as fully assembled.

Conventional shading is illustrated for purposes of highlighting the line drawings, but forms no part of the claimed design.

1 Claim, 20 Drawing Sheets
